REVERSIBLE PROPELLER

Ross Earl Bell, Vancouver, British Columbia, Canada

Application September 20, 1947, Serial No. 775,309

1 Claim. (Cl. 170—160.36)

1
My invention relates to improvements in reversible propellers.

The object of the invention is to provide a reversible propeller which is simple in construction and so designed that in case of damage to a blade, said blade may be removed and replaced without removing the propeller from its shaft or interfering in any way with the journalling of the propeller shaft and adjusting sleeve.

Hitherto it has been impossible to obtain optimum efficiency from a reversible propeller when operating in forward and reverse directions and to prevent drag in these directions and also when the propeller is operating in neutral and in consequence nearly all of such propellers are less efficient in operation in every one of their running positions than the conventional solid propeller.

In view of the above objection, the present invention is designed to be most effectively streamlined and so constructed generally that its efficiency is equal to the conventional solid propeller when set to operate in a forward direction and to allow the loss of efficiency which is now unavoidable in reversible propellers, to be taken when said propeller is set to run in reverse direction, or when high efficiency is not essential.

Referring to the drawings:

Fig. 1 is a front elevational view of the invention.

Figs. 2, 3 and 4 are transverse sectional views of the blades taken on the lines 2—2; 3—3 and 4—4 of Figure 1 respectively.

Fig. 5 is a sectional detail view of the pivotal mounting of each blade.

Fig. 6 is a sectional view of the propeller hub.

Figs. 7, 8 and 9 are side elevational views of the propeller in forward, neutral and reverse positions respectively.

In the drawings like characters of reference indicate corresponding parts in each figure.

The numeral 11 indicates generally a propeller shaft upon which a hub 12 is secured. The hub 12 is provided with a cylindrical portion 13 and a tapering trailing end 14. Extending radially from the portion 13 of the hub 12 are pivot pins 15 having a cylindrical bearing portion 16, a thread 17 and a reduced stem portion 18, and on each of the pivot pins 15 a propeller blade 20 is fitted.

Each blade 20 has an inner face 21 which lies in a plane substantially touching the outer peripheral wall of the hub 12 and is drilled outwardly from said inner face with a hole 23 having an inner bore 24 and a counterbore 25 and

a thread 26 between said bores which is adapted to freely receive the thread 17. Each blade 20 is screwed onto its pivot pin 15 to prevent substantial endwise movement and to be rockingly supported on said pin with the cylindrical bearing portion journaled in the counterbore 25 of the hole 23 and the stem portion 18 journaled within the inner bore 24 of said pivot pin 15. Each blade is fitted with a bolt 27 which extends from its inner face and is disposed to the rear or toward the trailing edge of said blade. The blades are stream lined in cross section, as shown in Figures 2, 3 and 4, with their forward faces convexed transversely and their rear faces lying in substantially the plane of the chords of the sections shown.

Slidably mounted upon the shaft 11 is a hub shell 30 having tangential wings 31, each of which conform substantially to the rear part of the inner face 21 of the blade. The wings are slotted inwardly from their outer ends as at 32 to embrace the bolts 27. The hub shell 30 is fitted to a sleeve 34 which is journaled in suitable bearings, not shown, and said sleeve surrounds the propeller shaft 11 to rotate therewith.

Longitudinal slots 35 are formed in the hub shell 30 which straddle the pivot pins 15, so that when the said hub shell is moved rearwardly along the hub, the wings 31 through the bolts 27, rock the blades 20 about the pivot pins 15 until said pivot pins are disposed adjacent the inner ends of the slots 35 and the wings 31 are directly aligned with the inner faces 21 of the blades. When the wings 31 are so disposed, viz, with their edges parallel to the edges of the faces 21, the propeller is adjusted for forward driving and a minimum resistance to rotation is encountered from said wings because they are directly behind the said inner faces. As the sleeve 34 is moved forwardly the wings 31 are likewise forwardly moved, so that the forward edge of each of said wings will be exposed to side thrust from the water. The movement of the shell in a forward direction will first bring the forward and trailing edges into a plane parallel to the radial plane in which the pivot pins 15 are set, thus restraining them from exerting any thrust lengthwise of the shaft 12. A still further movement of the hub shell 30 in a forward direction will rock the blades to cause the propeller blades to exert a thrust in a rearward or reverse direction. In the last mentioned position, the side areas of the wings are exposed to their greatest extent and impose a resistance to rotation, but as speed and optimum propelling

thrust is not necessary in this direction the efficiency loss is unimportant.

What I claim as my invention is:

A reversible propeller comprising a hub shell and a hub telescopically mounted therein, said hub having a plurality of radially extending pivot pins, a propeller blade swingingly mounted upon each of said pins, means on the hub shell for rocking the blades upon their pins in response to endwise movement between the hub shell and the hub, each of said pins having a bearing portion at its inner end and at its outer end and a threaded portion between said bearing portions, each of said blades being bored to form journals about the inner and outer bearing portions and having an internal thread between said journals to fit the thread of the pin, said thread forming the sole means for retaining each blade upon its pivot pin.
